AIR CUSHION BOAT

Harold Branch, Laurel, and Richard H. Horton, Severna Park, Md., assignors, by mesne assignments, to National Research Associates, Inc., Laurel, Md., a corporation of Maryland

Filed Nov. 28, 1961, Ser. No. 67,728

Term of patent 14 years

(Cl. D71—1)

FIG. 1.

FIG. 2.

FIG. 3.

FIG. 4.

FIG. 5.

FIG. 1 is a perspective view of an air cushion boat, showing our new design;

FIG. 2 is an enlarged front view thereof;

FIG. 3 is a top plan view thereof;

FIG. 4 is a side elevational view thereof; and

FIG. 5 is an enlarged rear elevational view thereof.

The side not shown is substantially a mirror image of the side shown.

What is claimed is:

The ornamental design for an air cushion boat, as shown and described.
